UNITED STATES PATENT OFFICE

ROBERT W. BARKER, OF PHILADELPHIA, PENNSYLVANIA, ASSIGNOR TO HESS & BARKER, INC., OF PHILADELPHIA, PENNSYLVANIA, A CORPORATION OF PENNSYLVANIA

AUTOMATIC JACQUARD PUNCHING MACHINE

Application filed March 18, 1929. Serial No. 347,889.

My invention relates to a new and useful jacquard punching machine and it relates more particularly to a novel machine for stamping pattern cards for use in connection with jacquard controlled textile machinery, although my invention is also applicable to other punching operations where it is desired to provide successive perforations or other indentations in sheet material in some predetermined, though irregular spaced relation to each other.

My invention consists of a novel combination of punching mechanism, means to guide and intermittently to propel a piece of sheet material with respect to said punching mechanism at a predetermined rate and an adjustable pattern mechanism to operate upon the intermittently propelled sheet material according to a predetermined though variable sequence or pattern.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings, in which like reference characters indicate like parts:

Figure 1 represents a front elevation of a novel machine embodying my invention.

Figure 2 represents a top plan view of the gear train forming part of the novel machine of my invention.

Figure 3 represents a side elevation of the same.

Figure 4 represents a fragmentary sectional view taken on line 4-4 of Figure 3.

Figure 5 represents a perspective view of the starting cam for controlling the propulsion of the sheet material.

Figure 6 represents a perspective view of a stop cam for controlling the propulsion of the sheet material.

Figure 7 represents a perspective view of

the follower end of a control lever actuated by the two cams shown in Figures 5 and 6.

Figure 8 represents a top plan view of the machine embodying my invention, partly in section, on line 8-8 of Figure 1.

Figure 9 represents a front elevation, on an enlarged scale, of the material propelling mechanism and the control therefor.

Figure 10 represents a top plan view of a jacquard sheet punched by the novel machine embodying my invention.

Figure 11 represents a fragmentary rear elevation of the pattern wheel of the machine embodying my invention.

Figure 12 represents a section on line 12-12 of Figure 11.

Figure 13 represents a side elevation, on an enlarged scale, of a gauge or clamp for holding the sheet to be operated upon.

Figure 14 represents a section on line 14-14 of Figure 8, on an enlarged scale.

Figure 15 represents a section on line 15-15 of Figure 14.

In carrying out my invention I may utilize a punch press of any conventional construction having a base 1, with an overhanging frame 2, upon which is slidably mounted a vertical punch slide 3 in a usual manner, and in the upper part of which a pair of main bearings 4 and 5 are provided, in

which is journalled a crank or cam shaft 6 having a central eccentric cam or crank 7. The crank or eccentric cam 7 is interconnected with the punch slide 3 by means of an adjustable connecting rod 8, including the adjustment screw 9. Upon the cam or crank shaft 6 is fixedly mounted a clutch collar or driven clutch member 10, in which a clutch bolt or key 11 is slidably mounted.

The driving clutch member 12 is loosely mounted upon the shaft 6 and is directly connected or permanently affixed to the fly wheel 13 and the pulley 14, which are similarly loosely mounted upon the shaft 6 and retained thereon by the terminal retaining collar 15. The driving clutch member 12 is provided with an aperture 16 in its face,

in operative alignment with the end of the key 11, so that when the key is moved into engagement with the aperture 16 the driv-

100

ing clutch member 12 and the driven clutch member 13 will be operatively interengaged. A spring 17 normally urges the clutch key 11 into operative engagement with the aperture 16 in the driving clutch member 12.

A clutch control lever 18, pivoted upon the frame at 19, is provided with a camming arm 20 which normally lies in the path of the heel 21 of the clutch key 11 and thereby cams the clutch-key 11 in the direction of the arrow 22, against the force of the spring 17, thereby disengaging the same from the driving clutch member 12.

When it is desired to effect an engagement 15 between the driving clutch member 12 and the shaft 6, thereby to reciprocate the punch, the clutch control lever 18 is deflected in such a manner as to retract the cam arm 20 from operative alignment with the heel 21 of the clutch key 11. A friction brake 23 surrounds the driven clutch member 10, thereby to check the inertia of the crank shaft 6, punch slide 3 and connecting rod 8 when the same are disengaged from 20 the drive.

Upon the continuously revolving driving clutch member 12, I secure a sprocket wheel 24, which drives a lower shaft 25 in a continuous manner, through the sprocket chain 26 and the sprocket wheel 27 carried by said lower shaft 25.

The punch control mechanism and the sheet feeding or propelling mechanism are both driven from the shaft 25, in a manner to be described hereinafter.

An elongated horizontal table 28 is rigidly mounted upon the base 1 of the punch press. The sheet or jacquard strip 29 is supported upon the table 28.

The table 28 is provided with a longitudinal dovetailed guide rail 30, upon which a rack member 31 is slidably mounted, having uniformly spaced transverse ratchet teeth 32 upon its upper surface.

The leading end of the sliding rack 31 carries a clamping member 33 in which one end of the sheet to be punched, such as the jacquard strip 29, is detachably secured for the purpose of propelling past the punching device. Thus the clamp 33 is provided with a recess 34 in which the end of the strip fits, and is also provided with a spring pressed plunger or pin 35 adapted to enter a corresponding aperture 36 in the end of

the jacquard strip, thereby to retain the same in fixed spaced relation with respect to the sliding feed rack 31. The spring 37, confined between the transverse pin 38 and the upper guide and supporting bracket 39, serves to maintain the plunger 35 in its lowermost position.

The lower die 40 is detachably secured in the table 28 with its upper surface flush with the upper surface of the table, while a stripper plate 41 is fixedly mounted above

and in operative alignment with the lower die 40, spaced therefrom a distance substantially equal to the thickness of the sheet 29 to be punched, as shown particularly in Figures 14 and 15.

The punch 42 is mounted in the punch slide 3 in operative alignment with the die 40.

A pair of fixed guides 43 and 44 serve to guide the jacquard 29 as it enters between the punch and die.

Sheet propelling and punch controlling mechanism

The lower shaft 25 carries a bevelled gear 45 which is in mesh with a similar bevelled gear 46 carried by an inclined shaft 47 which is journaled at 48 in a bearing bracket 49 (Figures 2 and 3). The shaft 47 in turn is connected to a horizontal shaft 50, through a universal joint 51; said horizontal shaft 50 in turn being journaled at 52 in said bearing bracket 49. To the free end of the shaft 50 a concentric disk 53 is secured, likewise journaled in the bearing bracket 49, which in turn carries an eccentric pin 54.

Upon the eccentric pin 54 a pawl 55 is loosely mounted, having its lower end 56 in operative alignment with the teeth 32 of the rack 31.

The arm 57 of the pawl member 55 is urged upwardly by the helical spring 58, the upper end of which is supported by a suitable bracket 59.

The eccentricity of the pin 54 is such as to cause the lower end 56 of the pawl 55 to be displaced laterally with each revolution of the shaft 50 and disk 53, the distance of one tooth (32) on the rack 31, thereby displacing the rack 31 as well as the jacquard or other strip 29 carried thereby, the distance of one tooth (32).

A rotation of the shaft 50 is so timed with respect to the clutch key aperture 16 in the driven clutch member 12, as to effect the intermittent propulsion of the rack 31, and hence of the jacquard strip 29, during the interval when the punch 42 is removed from the die 40, that is, during the latter part of the up-stroke and the beginning of the down-stroke of the punch.

The operation of the clutch key 11 of the punch is effected by the pattern wheel 60 carried by the horizontal shaft 61 which is likewise driven in a continuous manner from the horizontal shaft 25 through the train of gears shown particularly in Figures 1, 2 and 3.

Thus the shaft 25 carries a driving pinion 62, which is in mesh with a gear 63, carried by a counter-shaft 64 journaled in suitable bearings 65 in the lower frame 66. The counter-shaft 64 in turn carries a pinion 67 which is in mesh with a similar pinion 68

carried by a second counter-shaft 69, journalled in the bearings 70 similarly carried by the lower frame structure 66. The second counter-shaft 69 carries a pinion 71 which is in mesh with a gear 72 carried by the pattern wheel shaft 61, which latter is journalled in the two bearings 73 carried by the lower frame structure 66.

The pattern wheel 60, shown enlarged in Figure 12, is a cup-shaped disk having a series of spring-pressed plungers or "pins" 74 mounted in the face 75 thereof. The spring-pressed plungers or "pins" 74 are uniformly spaced at predetermined intervals throughout the periphery of the pattern wheel 60. Any suitable number of "pins" 74 may be provided, though in the instant machine 50 "pins" are used, as this number has been found to be suitable for one of the purposes for which this machine is intended, (though in the drawings the full fifty pins are not shown).

Each spring pressed plunger or "pin" 74 is slidably mounted in a suitable bearing 76, and is provided at its inner end with two flanges 77 and 78 spaced from each other a suitable distance. A bracket 79 is provided within the pattern wheel 60 corresponding to each of the "pins" 74 and is secured by a screw 80 passing through the flange 81 of the pattern wheel. A helical compression spring 82 is confined between the inner end of the "pin" 74 and the screw 80, tending to urge said pin outwardly. A spring-pressed locking bolt 83 is carried by the bracket 79, and actuated by a helical compression spring bracket 84, whereby the "pin" 74 may be locked in its innermost position with the outer end thereof flush with the face 75 of the pattern wheel thereof. This is accomplished by depressing the pin 74 inwardly, withdrawing the spring-pressed bolt 83 by means of its handle 85 and placing the free end of the locking bolt 83 between the two flanges 77 and 78 of the pin 74, thereby retaining said "pin" in its inner position. By so locking the "pin" in its inner position the same is rendered inoperative.

A vertical follower slide 86 is slidably mounted in a pair of supporting brackets 87 and 88, and is arranged generally tangentially with respect to the pattern wheel 60 and in operative alignment with the "pins" 74 thereof, so as to be successively engaged and raised upwardly by each of the "pins" 74 which may be in their outer or operative positions.

The upward displacement of the follower slide 86 is transmitted to a lever 89 pivoted at 90 upon the lower frame structure 66, to which lever the upper end of the slide 86 is pivotally fastened at 91. The free end of the lever 89 is in turn connected to the free end of the clutch control lever 18, by means of a connecting rod 92, pivotally secured to

the free ends of said two levers at 93 and 94 respectively.

The camming arm 20, forming the one end of the control lever 18, is urged upwardly into an operative position by a helical compression spring 95 which surrounds the vertical rod 96, which is pivotally connected to said camming arm 20, and the lower end of which passes through and is guided by a stationary bracket 97, which latter also supports the lower end of the spring 95. The connecting rod 96 is in turn connected with a manual control lever 98 through the connecting rod 99. Thus, by the depression of the manual control lever 98, the camming arm 20 may be retracted so as to permit the operation of the clutch key 11 and hence so as to operate the punch.

The spring 95 therefor serves normally to maintain the camming arm in its upper or operative position, thereby rendering the punch inactive, and the spring 20 also serves to maintain the follower slide 86 in its lowest position.

As each active "pin" 74 (a "pin" in its outer position) engages the lower end of the follower slide 86 (shown in Figure 3), as the pattern wheel 60 revolves continuously in the direction of the arrow 100, the follower slide 86 is raised a fixed distance, sufficient to retract the camming arm 20 and to render the punch active for one stroke.

As the jacquard strip 29 is therefore propelled intermittently in the direction of the arrow 101 (Figure 8) the punch 42 may be caused to act upon the jacquard strip at predetermined irregular intervals as may be desired, by merely positioning the appropriate pattern "pins" 74 in the outer or active position and depressing the other "pins." Thus, to punch any particular pattern upon a jacquard strip 29, it is merely necessary to set the pattern upon the pattern wheel 60, by properly positioning the pattern "pins" 74 thereof, and then to feed the jacquard strip 29 through the punch with the result as indicated in Figures 8 and 10.

The number of pattern "pins" 74 provided upon the pattern wheel 60 is greater than the number of positions or stitches of any particular design or pattern that may be desired, so that a jacquard strip 29 though containing punch positions or jacquard positions in excess of fifty, may be completely punched upon this machine, in a fully automatic manner, by merely repeating the pattern (of less than fifty positions) as often as the pattern may occur upon the particular jacquard strip.

Thus, for instance, a pattern of twelve positions occurring eight times upon the jacquard strip is set on the pattern wheel 60 four times in succession, thereby utilizing forty-eight "pins" of the total 50; the remaining two "pins" being rendered in-

active and the jacquard strip is thus punched fully by two revolutions of the pattern wheel 60.

In order that there should be no gap on the jacquard strip, between the first and second revolution of the pattern wheel 60, or between any two successive revolutions thereof, corresponding to the number of pattern "pins" at the end of the revolution which had not been used (the two last "pins" in the above example), it is necessary to render the strip-propelling mechanism inactive for a period corresponding to the unused pattern "pins" at the end of each revolution of the pattern wheel. This is accomplished by a pair of cams 102 and 103 shown particularly in Figures 5, 6 and 3.

These two cams are provided with two opposed inclined camming faces 104 and 105 respectively and are provided with dove-tailed bases 106 and 107 which are adapted to seat within the annular under-cut or dove-tailed channel 108 in the face of the pattern wheel 60, as shown particularly in Figures 3 and 12. The set screws 109 and 110 are threaded through suitable apertures 111 and 112 in the two cam blocks 102 and 103 respectively, for the purpose of fixing said cam blocks in any desired position along the annular channel 108. The cam block 102 is fixed at the first position of the pattern on the pattern wheel, while the cam block 103 is positioned immediately after the last pattern position on the pattern wheel.

A follower lever 113 is pivotally mounted at 114 upon the stationary bracket 115. The lower right angular end 116 of the follower lever 113, is provided with a generally cylindrical follower roller or member 117, which is in operative alignment with the camming surfaces 104 and 105 of the two cam blocks 102 and 103 respectively. Thus the cam block 102 at the beginning of the pattern-setting of the pattern wheel 60 will cause the deflection of the follower lever 113 in a manner indicated by the arrows 118 (Figure 1), while the cam block 103, at the end of the pattern-setting, will cause an opposite deflection of the follower lever 113 as indicated by the arrows 119 (Figures 1 and 9).

The upper free end of the follower lever 113 is pivotally connected, at 120, to one end of a horizontal slide 121 which is slidably mounted in a stationary guide 122. The free end 123 of the slide 121 is inclined as shown particularly in Figures 1 and 9, and is in operative alignment with a correspondingly inclined surface 124 of the jacquard propelling pawl arm 57. Thus when the lever 113 is deflected in the direction of the arrow 119 (Figure 9) by the cam block 103, positioned at the end of the pattern-setting of the pattern wheel, the in-

clined end 123 of the slide 121 engages the inclined end 124 of the pawl arm 57, riding up upon the same, and thereby deflecting the pawl arm and retaining it in a deflected position with the operative end 56 thereof raised above and clear of the teeth 32 of the rack 31 and thereby automatically stopping the propulsion of the jacquard strip. As the pattern wheel revolves further, the cam block 102, having an oppositely positioned cam surface 104, engages the follower 117 and deflects the lever 113 in the direction of the arrow 118 and thus retracts the slide 121 and again releases the pawl 56 into operative engagement with the teeth 32 of the rack 31. By this means the propulsion of the jacquard strip is again initiated at the beginning of the pattern-setting and the pattern may thus be repeated upon the jacquard strip without any gap or break between the successive revolutions of the pattern wheel.

In order automatically to stop the propulsion of the jacquard strip when it is fully punched throughout its desired length a stop 125 is adjustably secured to the rack 31 by means of a set screw 126. This stop 125, when properly set with respect to the end of the jacquard strip, will engage a pin 127 carried by the slide 121 and thereby move said slide forwardly into an operative position and thus render the propelling pawl 56 inactive.

Having thus described my invention what I claim as new and desire to secure by Letters Patent, is:—

1. The combination with a punching mechanism of means for intermittently propelling a piece of sheet material through said punching mechanism at a predetermined rate, and adjustable pattern mechanism comprising a rotary disc and a plurality of pins arranged peripherally of said disc, operative connections from said pattern mechanism to said propelling means, and operative connections from said pattern mechanism to said punching mechanism.

2. In a device of the character stated, a punching mechanism, means to drive the same, a clutch intermediate of and adapted operatively to engage said punching mechanism and said driving means, a slide mounted in operative alignment with said punching mechanism and adapted to guide a piece of sheet material therethrough, a rack carried by said slide, a reciprocatory pawl in operative alignment with and adapted intermittently to propel said rack, means intermediate said pawl and said driving means for operating the former in synchronism with the latter, a rotary pattern mechanism operatively connected with said driving means including a series of adjustable camming members arranged in a generally

circular orbit, means intermediate said camming members and said clutch for actuating the latter, and adjustable means carried by said rotary pattern mechanism for controlling said work propelling pawl.

5 3. In combination, a punching mechanism, means for intermittently propelling a piece of sheet material thru said punching mechanism, an adjustable pattern mechanism comprising a rotary disc, a plurality of pins arranged thereon, operative connections from said pins to said punching mechanism, and means intermediate said disc and said propelling mechanism for rendering said propelling mechanism idle during predetermined movements of said rotary disc.

10 4. A device of the character stated comprising an intermittently operable punch press, driving means therefor, propelling means intermittently to feed a sheet of material thru said press at a predetermined rate, an adjustable pattern mechanism comprising a rotary disc, cams on said disc, a plurality of pins arranged on said disc, means for rendering certain of said pins inoperative, connections intermediate the operative pins on said disc and said press, and means actuated by said cams whereby, said propelling mechanism may be rendered 15 25 30

idle during predetermined intervals. 5. The combination with a punching mechanism of a propelling mechanism for intermittently propelling a piece of sheet material thru said punching mechanism at 35 a predetermined rate, and an adjustable pattern mechanism adapted to synchronize the operation of said punching mechanism and said propelling mechanism comprising a rotary disc, a plurality of pins arranged thereon, means for rendering certain of said pins inoperative, connections intermediate the operative pins on said disc and said punching mechanism for controlling the latter, cams on said disc, and connections intermediate said cams and said propelling mechanism, certain of said cams being adapted to render said propelling mechanism inoperative and certain of said cams being adapted to render said propelling 40 45 50

6. A pattern mechanism for controlling a punch press or the like which includes a punching mechanism and means for propelling a sheet of material thru said punching mechanism, comprising a rotary pattern disc, a plurality of pins arranged thereon, a plurality of cams carried by said disc, operative connections intermediate said pins and said punching mechanism for controlling the latter and operative connections intermediate said cams and said propelling mechanism, whereby, said propelling and punching mechanisms may be operated synchronously and in a uniformly irregular 55 60 65

7. A pattern mechanism for controlling a punch press or the like which includes a punching mechanism and means for propelling a sheet of material thru said punching mechanism, comprising a rotary pattern disc, a plurality of pins arranged thereon, means for rendering certain of said pins inoperative, operative connections intermediate the operative pins on said disc and said punching mechanism, for controlling the latter and means for rendering said propelling means operative and inoperative at predetermined intervals, whereby, said propelling means and punching mechanism may be operated synchronously and in a uniformly irregular relation to each other.
